[57] CLAIM

The ornamental design for a urine collection device, as shown and described.

DESCRIPTION

FIG. 1 is a top, left-side perspective view of a urine collection device, showing our design;

FIG. 2 is a bottom left-side perspective view of the device of FIG. 1;

FIG. 3 is a left-side plan view of the device of FIG. 1;

FIG. 4 is a top-plan view of the device of FIG. 1;

FIG. 5 is a front elevational view of the device of FIG. 1;

FIG. 6 is a rear-elevational plan view of the device of FIG. 1; and,

FIG. 7 is a bottom-plan view of the device of FIG. 1.
